UNITED STATES PATENT OFFICE.

THOMAS DUNCAN, OF CHICAGO, ILLINOIS, ASSIGNOR TO THE SIEMENS & HALSKA ELECTRIC COMPANY OF AMERICA, OF CHICAGO, ILLINOIS, A CORPORATION OF ILLINOIS.

ELECTRIC METER.

SPECIFICATION forming part of Letters Patent No. 698,650, dated April 29, 1902.

Application filed August 3, 1899. Serial No. 725,976. (No model.)

To all whom it may concern:

Be it known that I, THOMAS DUNCAN, of Chicago, in the county of Cook and State of Illinois, have invented certain new and useful improvements in Electric Meters, (Case No. 53,) of which the following is a specification.

This invention relates to improvements in induction motor-meters for alternating-current work, and particularly to methods and means of obtaining in such meters a magnetic field in quadrature with the electromotive force which it represents.

The invention consists in the matters hereinafter described, and particularly pointed out in the appended claims, and will be fully understood from the following detailed description of the constructions illustrated in the accompanying drawings, in which—

Figures 1 and 2 are partially diagrammatic plan views of meters embodying my invention. Fig. 3 is a similar front elevation of still another meter construction embodying my invention, but modified somewhat from either form previously shown. Figs. 4, 5, 25 and 6 are vector diagrams of the essential current effects.

As shown in Fig. 1, A designates the rotary armature of the meter, B and C the series and volt field-coils, and D an impedance-coil connected in series with the volt field-coil C in a shunt-circuit between the main leads w and w' of the work-circuit. D' is a secondary impedance-coil placed in inductive relation to the coil D and connected in a second shunt-circuit, in which the volt field-coil C is also connected in series. The terminals d and d' of the two coils D and D' are shown as connected to the leads w and w' , respectively, of the work-circuit, while their opposite terminals d^2 and d^3 are connected, through the volt field-coil C, with the leads w' and w , respectively. Adjustable resistances r and r' are shown as inserted in the terminals d' and d^3 to assist in the adjustment and calibration of the meter, and as a further improvement a starting-coil D² is shown as inserted in the secondary shunt-circuit between the coils C and D' to assist in overcoming the friction and inertia of the meter, especially 45 under light working loads. The construc-

tion shown in Fig. 2 is similar, except that the secondary coil D', instead of being wound upon the same magnetic core D³ with the primary coil D, is wound upon a separable armature D⁴, which for purposes of further adjustment may be separated from the main core D³ by space-blocks s of any desired thickness. This is also true of the construction shown in Fig. 3. An additional adjustable resistance r^2 is also shown in Fig. 2 as inserted in the terminal d^2 of the primary shunt-circuit, while in Fig. 3 only the single adjustable resistance r' in the terminal d^3 of the secondary shunt-circuit is provided. The friction-coil D² is not shown in Fig. 3, but can be supplied in any suitable manner. In all of said views, G indicates the alternating-current generator, and L and M the lamps and motors constituting the load.

Any suitable mechanism R may be employed to register the revolutions of the armature, and a magnetic drag S may be applied in the usual manner to maintain the number of revolutions proportional to the torque exerted, such devices being indicated in Fig. 3, but omitted from the other views of the drawings for the sake of simplicity of illustration. These features, however, constitute in themselves no part of the present improvements and are mentioned merely for the purpose of enabling the complete installation to be clearly understood.

The essential phase relations resulting in the present improvement are shown graphically in Figs. 4, 5, and 6, in which the line E represents the impressed electromotive force of the work-circuit, and F the primary shunt-current, which will naturally be lagged somewhat less than ninety degrees behind the electromotive force E by the impedance-coil D, Fig. 4. The secondary impedance-coil D' will act as a primary on the coil D and induces a secondary current F' in the primary shunt-circuit, so that the total effective current through this circuit is the resultant f, obtained by completing the parallelogram on lines F and F', Fig. 5. This may still lag less than ninety degrees; but the total current supplied to the volt field-coil C includes not only such resultant, but the secondary shunt-

current F^2 through the coil D^7 , the effect of which is to produce a final resultant F^3 , which by suitable adjustment, as by means of either or all of the adjustable resistances r , r' , and r^2 , may be given the exact ninety-degree lag desired.

In the preferred embodiment of the invention, as illustrated, the pressure-winding is subdivided into two coils, the coils having a common terminal, which is connected with one side of the distribution-circuit through an impedance-coil, the remaining terminal of one of the remaining pressure-coils being connected with the other side of the distribution-circuit through a second impedance-coil, the impedance-coils being preferably inductively related, while the remaining terminal of the remaining pressure-coil is also connected with the latter side of the distribution-circuit.

I claim as my invention—

1. An electric meter provided with an armature, a series coil connected in series in the work-circuit, a volt-coil connected in two shunt-circuits between the main leads of the work-circuit, and impedance-coils inserted in each of said shunt-circuits, substantially as described.

2. An electric meter provided with an armature, a series field-coil connected in series in the work-circuit, a volt field-coil connected in two shunt-circuits between the main leads of the work-circuit, and impedance-coils inserted in each of said shunt-circuits and arranged in inductive relation to each other, substantially as described.

3. An electric meter provided with an armature, a series field-coil connected in series in the work-circuit, a volt field-coil connected in two shunt-circuits between the main lead of the work-circuit, impedance-coils inserted in each of said shunt-circuits, and a starting-coil inserted in one of said shunt-circuits, substantially as described.

4. In a meter, the combination with current and pressure windings, the pressure-windings being subdivided into two coils having a common terminal, an impedance-coil connecting the said common terminal with one side of a distribution-circuit, and a second impedance-coil connecting the remaining terminal of a pressure-coil with the other side of the distribution-circuit while the remaining terminal of the remaining pressure-coil is also connected with the latter side of the distribution-circuit, the impedance-coils being inductively related.

5. In a meter, the combination with current and pressure windings, the pressure-windings being subdivided into two coils having a common terminal, an impedance-coil connecting the said common terminal with one side of a distribution-circuit, and a second impedance-coil connecting the remaining terminal of a pressure-coil with the other side of the distribution-circuit while the remaining terminal of the remaining pressure-coil is also connected with the latter side of the distribution-circuit, the impedance-coils being inductively related.

6. In a meter, the combination with current and pressure windings, the pressure-windings being subdivided into two coils having a common terminal, an impedance-coil connecting the said common terminal with one side of a distribution-circuit, a second impedance-coil connecting the remaining terminal of a pressure-coil with the other side of the distribution-circuit while the remaining terminal of the remaining pressure-coil is also connected with the latter side of the distribution-circuit, the impedance-coils being inductively related.

7. In a meter, the combination with current and pressure windings, the pressure-windings being subdivided into two coils having a common terminal, an impedance-coil connecting the said common terminal with one side of a distribution-circuit, a second impedance-coil connecting the remaining terminal of a pressure-coil with the other side of the distribution-circuit while the remaining terminal of the remaining pressure-coil is also connected with the latter side of the distribution-circuit, and a phase-modifying device r' connected in shunt of the distribution-mains, substantially as described.

8. In a meter, the combination with current and pressure windings, the pressure-windings being subdivided into two coils having a common terminal, an impedance-coil connecting the said common terminal with one side of a distribution-circuit, a second impedance-coil connecting the remaining terminal of a pressure-coil with the other side of the distribution-circuit while the remaining terminal of the remaining pressure-coil is also connected with the latter side of the distribution-circuit, the impedance-coils being inductively related, and a phase-modifying device r' connected in shunt of the distribution-mains, substantially as described.

In testimony that I claim the foregoing as my invention I affix my signature, in presence of two subscribing witnesses, this 25th day of July, A. D. 1899.

THOMAS DUNCAN.
